UNITED STATES PATENT OFFICE

2,017,073

SPRING NEEDLE PILE FABRIC KNITTING MACHINE

David Pelton Moore, Avon Park, Fla.

Application June 25, 1931, Serial No. 546,893

7 Claims. (Cl. 66—147)

The present invention relates to improvements in methods and apparatus for making knitted pile fabrics, one object of the invention being a method for producing a knitted pile fabric so that the pile as the fabric is knitted upon the knitting machine will lie longitudinally of the fabric, and not transversely as is the present case.

Another object of this invention is the provision of an apparatus including a knitting machine and a fiber feeding attachment therefor by means of which knitted pile fabric with the pile extending longitudinally is produced, there being a brushing device operable preferably from the attachment for simultaneously brushing the pile and "setting" it in the desired longitudinal direction.

Another object of this invention is the provision of a machine of this type in which spring needles can be employed to receive and knit in the fibers fed thereto by a fiber feeding device so that a material similar to that set forth in my U. S. Letters Patent No. 1,791,741, granted February 10, 1931, can be produced on a spring needle knitting machine of the "up" or "down" feed type, instead of on a latch needle machine as has previously been contemplated.

Still another object of the present invention is the provision of a fiber feeding attachment which can be readily coordinated with a spring needle knitting machine to hold the knitted material or web down upon the shanks of the needles during the passage of such needles through the fiber feeding brush, said holding means either being a member of the attachment or associated with the knitting machine.

Still another object of the invention is the provision of an auxiliary high speed doffing brush for brushing the fibers after being knitted in a longitudinal position relatively to the fabric.

Still another object of the invention is the provision of an attachment which can be used one to each yarn feed of the knitting machine so that a plural number of fiber feeding attachments can be used and all operated in synchrony with the movement of the needle carrier of the knitting machine.

Still another object of the present invention is the provision of automatic means for halting the machine should the fiber sliver become too thin or give out in any one of the attachments.

Still another object of the present invention is the designing of the speed ratios between the peripheral speed of the fiber feeding brush and the needle cylinder, whereby the desired quantity of the fibers is fed to the needles, so that the needles are substantially to all practical purposes at "standstill" or nearly so position while receiving the fibers, and in which the wear upon the needles is greatly reduced.

Still another object of the present invention is

provision of an attachment which can be easily and quickly attached and detached from the present type of spring needle knitting machines, using the main supporting means similar to those used for attaching the yarn feeds, so that the attachment can be installed and removed by the knitters and readily adjusted to obtain the desired relative position of the fiber feeding brush to the needles of the machine.

With the foregoing and other objects in view 10 and as will presently appear as the description proceeds, it will be apparent that many changes in the details of construction and arrangement of the parts may be resorted to and still be well within the purview of what is claimed. 15

In the accompanying drawings:—

Figure 1 is a side elevation of the attachment as applied to a spring needle knitting machine, which latter has only a portion of its needle carrier or cylinder in diagrammatic section. 20

Fig. 2 is a section taken on line 2—2 of Fig. 3.

Figure 3 is an elevation of the attachment looking from the knitting machine.

Figure 4 is a section on line 4—4 of Fig. 1.

Figure 5 is a cross section through the pile setting brush.

Figure 6 is a section taken on line 6—6 of Fig. 1.

Figure 7 is a section taken on line 7—7 of Fig. 1.

Figure 8 is a top plan view and section, showing the supporting and attaching member for attaching the fiber feeding device or attachment to the knitting machine. 30

Figure 9 is a side elevation of a napping brush showing its use with a "top" or "up" feeding knitting machine.

Figure 10 is a front elevation thereof.

Figure 11 is a view similar to Fig. 9 showing the pile setting brush in use upon a "down" feeding knitting machine.

Figures 12 and 13 are details of a modified form 40 of presser to be used in lieu of a rotary disk type.

Referring to the drawings, the numeral 10 designates the table or bed plate of a spring needle machine, having the clamping bolts 11, and a knitting or needle carrier or cylinder 12. This 45 cylinder is driven in the usual manner by a center drive G and has disposed relatively thereto as is usual, the thread or yarn guides and knitting needle controlling elements (not shown).

The fiber feeding attachment or device A, is 50 composed of two side frames or plates 14 and 14', connected together by tie-rods 15, and is provided with adjustable and clamping supports or bolts 16, which in turn are adjustably connected to the slotted plates 17, two to each attachment. 55 These elements are of the type now used to support the yarn feeding elements relatively to the cylinder.

Mounted in the frames are the main carding drum 18, two feeding cylinders 19 and 19', two 60

feed-in rollers 20 and 20', and two pairs 21 and 22, respectively, of assisting carding cylinders, all of which are mounted to rotate in the direction of the arrows, Fig. 2. The carding clothes of these cylinders and drum are of the bent knee type, while the rotary fiber feeding brush 23, which receives its load from the main drum 18, is provided with the radially disposed relatively long stiff pins 24. The body of this clothing carrying these pins 24, is composed of rubber and fabric, with sufficient rubber to anchor the pins. These pins are bent U-shaped with the junction portion upon the rear face of the fabric, and by this arrangement are permitted to flex from and by the rubber of the fabric, so that the fibers are fed with a more even distribution upon the needles 27.

When this fiber feeding attachment is used with the spring needles 27, the same must be adjusted so that the center line 25 of the brush 23 will be just at or below the ends 26 of the needles 27, and with the ends of the pins 24 just slightly intermeshing or interdigitating with the needles 27 as the cylinder 12 and the brush are rotated in coordination. By this arrangement fibers taken by the brush 23 from the drum 18 will be wiped so as to enter the space *a* of the needles 27 to be brushed upwardly and seated in the loop *b* of the needles; and as the speed of the cylinder 12 is so adjusted as to move say 1 inch while the periphery of the brush 23 is moving 7 to 8 inches, the needles are substantially stationary when they move across the teeth of the brush 23. This ratio of approximately between 7 and 8 to 1, has been arrived at after very many experiments, and it has been found that a better fabric is produced, that the needles will not be overcrowded and that less wear due to friction is caused both upon the beards and hooks of the needles and the ends of the teeth 24.

It is also desirable when the needles are presented to and are passing through the brush 23, that the edge 28 of the knitted material 29, be below the space *a* of the needles, thus leaving the beards of the needles free to receive the fibers. To accomplish this, I prefer to use a circular disk presser 30, rotatably mounted on a stud 31, which in turn is carried by an adjustable arm 32, supported by the frame 14 in such a manner as to be presented upon the side of the needles inside of the brush 23, as shown in Figure 1. It is also possible to support the presser 30 from one of the clamping supports 33. Also in place of the circular disk presser 30, the curved presser plate 33', as shown in Figs. 12 and 13 may be used.

In some classes of fabric, it is desirable that the pile be laid longitudinally, and this is at present accomplished by brushing the pile face of the completed fabric, but in the present instance, means have been provided to accomplish this result directly and simultaneously with the knitting operation. Normally as the cylinder 12 rotates, the pile is pulled slightly in the opposite direction to the movement of said cylinder, and consequently the pile will lie transversely or nearly so on the material as it is taken from the machine. To prevent this, and to cause the pile to lie longitudinally of the fabric during the knitting thereof, a rotary brush 34 is attached to and carried by the shaft 35, upon which is mounted the brush 23, or as shown in Figs. 9, 10 and 11, a brush 75, independently of but which may be operably connected to the shaft 35, by a coupling 70 and flexible shaft 71 may be employed. When the latter is used, with an up feed spring needle

machine, it is mounted as shown in Fig. 9, wherein, a supporting bolt or member 16, supported by a member 17, is so mounted that the apertured foot 74, fits upon the upper end 76 of the bolt support 16', with the curved arm 73, supporting the short shaft 72 with the brush upon the outside of the cylinder 12', to brush upwardly the pile of the knitted material 29', while supported in and being knitted by the spring needles 27'. Or when the brush is used with a down feed, or latch needle machine, the parts are mounted as shown in Fig. 11, wherein the base 77 of the knitting machine has adjustably attached thereto as at 74' and 75', the curved arm 73', so that brush 75, acts downwardly upon the pile of the knitted material 79, while supported by the latch needles 78. This can also be used with down feed spring needles. The bristles of the brush 75 are straight radially disposed wire or hair and merely brush to set the pile and do not tear, nap, teazle or produce a nap from the web of the fabric, as the present pile is formed from short loose fibers folded upon the individual needles and knitted in with the basic yarn, so that the free ends of the fibers are merely brushed or set in the desired direction. The flexible shaft 71 is of sufficient length to permit the brush 75 to be mounted to act upon the knitted material slightly in advance of the engagement of the material by the presser 30—33, and where desired the speed of the brush 30 75 may be increased or diminished by the use of gearing adjacent the short shaft 72. This may be desirable when it necessary to overcome the tendency of the pile to lie inclinedly or transversely, but in practice a brush 75 approximately $\frac{1}{4}$ inch greater in diameter than the brush 23 will perform the desired setting of the pile or brushing it in the desired direction.

Although the present fiber feeding attachment may be driven in any desired or convenient manner to the end that it may be operated in timed relation to the needle cylinder 12, one method of driving it from a knitting machine will entail the use of a center gear drive as shown in U. S. Patent No. 32,241, to in turn drive the gear 45. 45 A gear 36 is fast to the shaft 18' and has a gear 37 meshing therewith and carried by the shaft 38. This shaft 38 is journaled in a support 39 and carries a gear 40 upon its lower end. A journaled gear 41 meshes with the gear 40 and is 50 journaled in the bracket 43, so that the shaft 42 driven by a gear 45 may be moved at any desired angle to receive its motion from the knitting machine drive, or any other prime mover whereby synchrony can be had between the operation of 55 the attachment and the knitting machine. This shaft 42 may be flexible so that the attachment may be placed at various desired adjustments, and universal connections may be resorted to where necessary. By this arrangement, one of 60 these attachments to each yarn or thread feeding element of the knitting machine may be employed, the attachment being positioned just slightly ahead of its respective co-operative yarn feeding element. In practice, however, four fiber 65 feeding attachments are preferable, as it then places them at 90° positions, and permits sufficient room to accommodate the sliver or roving holding cans.

To support the shaft 35 and its brush 23 so 70 that the brush may be raised or lowered radially of the drum 18 to accommodate the use of the brush 23 upon various heights of needle cylinders, and also further to adjust the brush to take care of wear upon its teeth 24, the side frames 14—14' 75

are provided with arcuate openings 57, the detail construction of which is shown in Fig. 6. A journal box 56, is slidably mounted in each opening 57, and is held in its desired adjusted position by means of the set screws 63—63', the strips 60 and screws 60', permitting the box 56 to be positioned in the respective opening 57. A bearing block 62, is mounted for adjustable movement in the bore 61 of the box 56, and itself is provided with the eccentrically placed bore or bearing 66, for the shaft 35, a set screw 65 being provided to hold the block 62 in adjusted position. Thus by moving the box 56 in the openings 57 by means of set screws 63—63', the shaft 35 and its brush 23 will be moved up or down with the shaft 18' the center of the arc of the movement, while by rotating slightly the cam or eccentric blocks 62, the shaft 35 and its brush 23 will be moved to or from the drum 18.

As shown in Fig. 7, an adjusting means is provided for the shafts of the various carding cylinders, 21 and 22, so that any wear on the carding teeth thereof may be taken care of, and also the relative positions of the cooperating pairs of cylinders may be changed. In this instance the frames 14—14', are provided with openings 61', to receive the adjustable blocks 62', which are locked in place by the set screws 65'. In each instance, the blocks 62—62' are provided with spanner recesses 67—67', to assist in the adjusting of elements, and where so desired a gauge may be marked upon each block and adjacent support therefor, so that the pairs of blocks can be more precisely adjusted and set.

It will be seen that with the attachment as herein shown and described, the brush 75 will brush the free ends of the fibers that form the pile while held in the needles upwardly and out of the way of the free ends or barbs of the needles and at a point just previous to the action of the presser disk 30 thereon. Thus the loop of the yarn and the fibers held in the hooks of the needles will be pressed downwardly and moved on to the shank of the needles, so that a free and clear hook will be presented to first receive the next tuft of fibers and just previous to the placing of the yarn within the hook, the release of the material upon the shank by the presser disk 30, permitting the loop and the fibers then held upon the shank to rise up over the depressed barb or point of the needle and to embrace the yarn and fibers now in the hook of the needle which is then formed in to the next succeeding loop and fiber combination. Thus the brush 75 insures the positioning of the free ends of the fibers of the last formed loop and also against the falling of the free ends of fibers thereabove, and permits with the action of the disk 75, the presentation of a clear needle hook to receive the next loop forming yarn and the next pile forming fibers therein. By this means the breakage of needles due to overcrowding and packing of the previously knitted fibers is overcome.

From the foregoing description taken in connection with the drawings, it is evident that there has now been provided a fiber feeding device operable upon spring needle machines as well as latch needle machines; that a means has been provided for adjusting the brush 23 so that it can be moved up for latch needles and dropped or lowered for spring needles; that the pile upon the material during the fiber feeding operation may be brushed to lie longitudinally of the fabric

and so that the free ends thereof are not in the way of the succeeding fiber feeding operations but are clear of the needles, the former making it more easy to finish the material while the latter saves breakage and injury of the needles; and also by the formation of the frame 14—14' of substantially closed construction, as curved sheet 68 with the suction hose attaching nipple 69 may be provided to convert the complete machine into a suction head, so that loose fibers can be carried away from the machine during the fiber feeding operation, a low suction action being advisable and from and through the bottom of the machine.

What is claimed, is:—

1. A fiber feeding attachment for knitting machines including a frame, a carding means mounted therein, means for receiving the fibers from the carding means and for delivering the fibers to the needles of the knitting machine, a presser device carried by the frame and disposed in spaced relation to the latter means, whereby the said latter means and the presser device are upon opposite sides of the needles, and a pile setting means is operably connected to the carding means to be driven simultaneously therewith. 25

2. A fiber feeding attachment for knitting machines including a frame, a carding means mounted therein, means for receiving the fibers from the carding means and for delivering the fibers to the needles of the knitting machine, a presser device carried by the frame and disposed in spaced relation to the latter means, whereby the said latter means and the presser device are upon opposite sides of the needles, said latter means being a rotatable brush and the presser 35 device being a rotatable disk, a shaft operated simultaneously with said brush, and a pile setting rotatable brush, operably connected to said shaft and disposed to operate upon the pile of the material carried by the knitting machine at a point 40 in advance of the engagement of the fiber feeding brush with the needles.

3. A fiber feeding attachment for knitting machines, including two side plates, carding elements journaled in the side plates operatively 45 associated between the plates, and a hood having a suction outlet encasing the greater portion of the upper edges of the plates and constituting therewith a suction head open through the bottom. 50

4. A fiber feeding attachment as claimed in claim 3, wherein the operating mechanism for the carding elements are external of the plates.

5. A fiber feeding attachment as claimed in claim 3, in which the journals of the carding elements are adjustable. 55

6. A fiber feeding attachment as claimed in claim 3, in which a fiber feeding brush is journaled in the side plates to receive the fibers from the carding elements, and in which a portion 60 thereof projects beyond the hood.

7. A fiber feeding attachment for knitting machines, including two side plates, carding elements mounted between the plates upon shafts journaled in the plates, a fiber feeding brush 65 journaled in the plates and disposed to receive the fibers from the elements, a hopper fitting over the edges of the two side plates to close the rear and top, the fiber feeding brush having a portion exposed beyond the front portions of the 70 side plates, and a suction hose attaching nipple carried by the hopper.

DAVID PELTON MOORE.
